FOREIGN PATENT DOCUMENTS

CN 201582666 9/2010

Primary Examiner — Clare E Heflin

(74) Attorney, Agent, or Firm — Stewart & Irwin, P.C.;
Dennis S. Schell(57) **CLAIM**

The ornamental design for a LED area light, as shown and described.

DESCRIPTION

FIG. 1 is a top front perspective view of the new design;
FIG. 2 is a front view thereof;
FIG. 3 is a right side view thereof;
FIG. 4 is a left side view thereof;
FIG. 5 is a top view thereof;
FIG. 6 is a bottom view thereof;
FIG. 7 is a rear view thereof;
FIG. 8 is a bottom rear perspective view thereof;
FIG. 9 is a sectional view taken along lines 9-9 of FIG. 5; and,
FIG. 10 is a sectional view taken along lines 10-10 of FIG. 5.
The broken lines shown in the drawings are for the purpose of illustrating aspects that form no part of the claimed design.
